Attorney

UNITED STATES PATENT OFFICE.

LEE MURDOCK, OF WAYNESBURG, PENNSYLVANIA.

WRENCH.

1,315,787.

Specification of Letters Patent.

Patented Sept. 9, 1919.

Application filed December 23, 1918. Serial No. 267,983.

To all whom it may concern:

Be it known that I, LEE MURDOCK, a citizen of the United States, residing at Waynesburg, in the county of Greene and State of Pennsylvania, have invented certain new and useful Improvements in Wrenches, of which the following is a specification.

This invention has reference generally to improvements in that class of inventions known as tools and more particularly relates to an improved wrench.

The primary aim and object of this invention is to provide a device of the above mentioned character designed to be used for turning pipe sections relative to each other while acting in conjunction therewith is an adjustable element for releasably holding the parts in a set position so that the device may be used for adjusting nuts et cetera.

More particularly, this invention contemplates the provision of a device of the above mentioned character embodying a shank and relatively movable jaws, one of the jaws being designed for movable and adjustable engagement on the shank while the remaining jaw is movably mounted on the first mentioned movable jaw, both of the jaws coacting with a cam head on the shank for insuring of an effective adjustment or turning of a pipe section relative to another pipe section.

It is a more specific object of this invention to provide a device of the above mentioned character wherein the shank and the two jaws are of novel construction and these component parts are designed to peculiarly coact with each other for producing an effective wrench.

Among the other aims and objects of this invention may be recited the provision of a device of the above mentioned character wherein the number of parts are comparatively few, the construction simple, the cost of production low and the efficiency high.

Other objects, as well as the nature, characteristic features and scope of this invention will be more readily apparent from the following description taken in connection with the accompanying drawings and pointed out in the claims, forming a part of this specification.

The invention is clearly illustrated in the accompanying drawings, in which:—

Figure 1 is a side elevation of the invention the outer movable jaw being shown in section,

Fig. 2 is a plan view of the improved wrench,

Fig. 3 is a cross section taken on line 3—3 of Fig. 1, and

Fig. 4 is a fragmentary perspective detail of the shank showing the cam head thereon.

Similar characters of reference are employed in all of the above described views, to indicate corresponding parts.

Referring now, more particularly, to the accompanying drawings, there is provided a shank 1 formed of metal desirably straight, one end thereof being slightly reduced as at 2 and formed with a slightly offset diagonally disposed cam head 3.

Movably mounted on the shank and coacting with the cam head is the inner movable jaw designated generally by the numeral 4. This jaw in the present instance is desirably of a substantially L-shaped configuration, the short portion 5 being provided with an opening 6 therethrough, one wall of which is curved as at 7 for riding engagement with the front face of the shank while the opposite wall extends diagonally as at 8 toward the corner of the jaw. The long portion 9 of the jaw 4 is curved slightly inwardly as at 10 and has the terminal portions thereof curved slightly outwardly as at 11, while the outer face of this terminal portion is provided with teeth 12 for providing in turn an engaging face for the jaw. In addition, the short portion of the movable jaw 4 is curved to provide a cam face 13 at the restricted ends of the openings 6 for coacting with the adjacent face of the cam head on the shank in a manner that will appear.

Coacting with the movable inner jaw and the cam head 3 is the movable outer jaw generally designated by the numeral 14 in the present instance being substantially L-shaped or hook-shaped including a shank 15 and an angularly disposed head 16 the inner face of the head and shank being formed with teeth 17 providing an engaging face for coacting with the engaging face 12, while in addition the shank is provided near its opposite extremity with an opening 18 for permitting of the slideable disposition of the jaw 14 about the long portion 9 of the jaw 4. The width of the opening 18 is substantially similar to the thickness of the portion 9 preventing relative transverse movement. However, one side wall of the opening is cut at an angle as at 19 while the opposite wall is abruptly rounded as at 20.

for coacting with the inner face of the curved portion 10 while the inner edge of the portion 16 is curved providing a cam face 21 for coacting with the cam head 3. This cam face 21 is so related to the cam head 3 that the latter also coacts therewith preventing accidental displacement of the outer L-shaped jaw from the inner L-shaped jaw.

10 Suitable resilient means such as a leaf spring 22 is employed for yieldingly holding the cam face 13 against the cam head 3 to, in consequence, insure of an engagement between the cam head 3 and the cam face 21 of the outer movable jaw, preventing the latter from being accidentally disengaged from the long portion 9 of the said inner jaw 4. The spring is preferably fastened at one end as by a screw 23 to the shank while the terminal of the resilient portion is seated in a recess 24 in the adjacent edge of the short portion 5 of the jaw 4, the arrangement being indicated in Fig. 1.

With a view toward providing the improved means for fastening the jaws in various positions of adjustment so that the wrench may be used for tightening the nuts et cetera an elongated set-screw is employed, the shank 25 thereof being adjustably mounted in a transverse opening 26 which communicates with the opening 6 so that the inner end of the threaded shank may frictionally engage the adjacent face of the shank 1 of the wrench upon the adjustment of the head 27 of the screw, as is apparent. Normally however, this set-screw is not in engagement with the shank 1 permitting of a free relative adjustment of the jaws 4 and 14. In other words, by the peculiar construction and arrangement of the jaws they are always arranged in operative relation with respect to each other and it is only necessary to arrange the engaging faces 17 and 12 of the jaws in engagement with an object such as a pipe section and swing the shank or handle 1 so that the cam head 3 will coact with the cam faces 13 and 21 on the adjacent edges of the respective jaws 4 and 14 to maintain the said engaging faces in effective engagement on the pipe section so that the latter can be adjusted relative to another stationary pipe section (not shown), as is apparent. In this connection it is to be understood that the swinging of the shank 1 causes a pressure to be exerted on the inner movable jaw so that the latter will move with the shank while at the same time the cam head will ride on the cam face 21 of the outer movable jaw to move this latter jaw in an opposite direction or toward the engaging face 12 on the inner movable jaw 4, the relation between the jaws being such that the greater the pressure applied, the tighter the engagement of the jaws with the object.

It is believed in view of the foregoing description that a further detailed description of the operation of the invention is entirely unnecessary. Likewise, it is believed that the advantages of the invention will be readily apparent.

Still further embodiments of the invention than those herein especially defined may be resorted to as conditions or preference may dictate, as may be in keeping with the hereto appended claims.

Having thus fully described the invention, what is claimed as new and desired to be secured by Letters Patent is:

1. A device of the character described including a shank, a cam formed integral with the outer end thereof and arranged diagonally thereof, an inner L-shaped jaw having the short portion slidably mounted on the shank and provided with a cam face for coacting with the cam head, resilient means for holding the cam face in yielding engagement with the cam head, and an L-shaped outer jaw having its long portion slidably mounted on the long portion of the L-shaped inner jaw and also provided with a cam face on the inner edge of the long portion for coacting with the head upon manipulation of the shank and being prevented from accidental displacement by its relation to the cam head.

2. A device of the character described including a shank, a cam head on one end thereof, an L-shaped inner jaw having an opening in the short portion of the L-shaped jaw for slidable disposition of the shank, the edge of the short portion of the jaw adjacent the cam head being designed to form a cam face, resilient means for holding said cam face in substantially yielding engagement with the shank, a substantially L-shaped outer jaw having an opening in its shank for slidable disposition about the long portion of the inner movable jaw and having its inner edge provided with a cam face for coacting with the cam head upon manipulation of the shank, and the cam face of the outer movable jaw being so related to the cam head that the cam head acts to prevent accidental displacement of the outer movable jaw from the inner jaw.

3. A device of the character described including a shank, a cam head on one end thereof, an L-shaped inner jaw having an opening in the short portion of the L-shaped jaw for slidable disposition of the shank, the edge of the short portion of the jaw adjacent the cam head being designed to form a cam face, resilient means for holding said cam face in substantially yielding engagement with the shank, a substantially L-shaped outer jaw having an opening in its shank for slidable disposition about the long portion of the inner movable jaw and having its inner edge pro-

vided with a cam face for coacting with the cam head upon manipulation of the shank, and a cam face of the outer movable jaw being so related to the cam head that the 5 cam head acts to prevent accidental displacement of the outer movable jaw from the inner jaw, and a set-screw mounted through the short portion of the inner movable jaw

and designed to be frictionally engaged with the shank at times for rigidly maintaining the jaws in various positions of adjustment.

In testimony whereof, I affix my signature hereto.

LEE MURDOCK.
